DESIGN FOR A RADIO CABINET

Raymond Jenkins, New York, N. Y., assignor, by
mesne assignments, to Milton Flamm, Forest
Hills, N. Y.

Application December 8, 1945, Serial No. 124,524

Term of patent 14 years

(Cl. D56—4)

To all whom it may concern:

Be it known that I, Raymond Jenkins, a citizen of the United States and resident of the city and State of New York, county of the Bronx, have invented a new, original, and ornamental Design for a Radio Cabinet, of which the following is a specification, reference being had to the accompanying drawing, forming part thereof.

Fig. 1 is a front elevational view of a radio cabinet, embodying my design.

Fig. 2 is an end elevational view thereof.

The rear of the cabinet not disclosed is substantially the same as the front of the cabinet disclosed, except that there are no dial or dial handles; the end of the cabinet not disclosed is substantially the same as the end of the cabinet disclosed.

I claim:

The ornamental design for a radio cabinet, substantially as shown and described.

RAYMOND JENKINS.
